[57] **CLAIM**

The ornamental design for a combined set of control panel and joy sticks for a video game machine, as shown and described.

DESCRIPTION

FIG. 1 is a perspective view of a combined set of control panel and joy sticks for a video game machine showing my new design;

FIG. 2 is a front view thereof;

FIG. 3 is a rear view thereof;

FIG. 4 is a top view thereof;

FIG. 5 is a right side view thereof; and,

FIG. 6 is a left side view thereof.

The broken line showing of a video game machine is for illustrative purposes only and forms no part of the claimed design.
